UNITED STATES PATENT OFFICE.

JOSEPH N. BURNO, OF CHICAGO, ILLINOIS, ASSIGNOR TO BUDDE & WESTERMANN, A CORPORATION OF NEW YORK.

COIN-CONTROLLED APPARATUS.

Application filed September 22, 1921. Serial No. 502,350.

To all whom it may concern:

Be it known that I, JOSEPH N. BURNO, citizen of the United States, residing at Chicago, county of Cook, State of Illinois, have invented certain new and useful Improvements in Coin-Controlled Apparatus, of which the following is a specification.

My invention relates generally to coin-controlled apparatus and more particularly to apparatus of this type intended for use in restaurants, lunch-rooms and the like where customers serve themselves, or where they are served at counters and carry the food to tables or armchairs.

One of the principal objects of my invention is compactness of construction. Heretofore many coin-controlled food vending devices have been used, but most of such devices have been so large and cumbersome that it has been impracticable and impossible to use them except in large restaurants and lunchrooms.

An object of my invention is to provide a device of the character described, in which the food compartments can be arranged one upon another as high as may be desired (usually ten high) with practically no loss of space between them. The usual devices of this kind are generally four or six compartments high, with a total height greater than that of my construction.

My invention is particularly adapted to be placed on luncheon counters and it may be used in a restaurant where the service is entirely automatic, or in conjunction with partial service by a counter attendant.

Another object of my invention is the adjustability of the device so that when it is arranged to be operated with a predetermined coin or number of coins it can be changed readily and quickly so as to operate with any other number of coins within a certain limit.

Other objects are simplicity and inexpensiveness of construction, durability and facility of operation.

A further object of the invention is ease of cleaning, rendering the device very sanitary.

Other objects and advantages will herein after appear in the following description.

I shall now describe the embodiment of my invention illustrated in the accompanying drawings and shall thereafter point out my invention in claims.

Figure 1 of the drawings is a front elevation of two compartments or sections of my invention showing the upper compartment in open position and lower compartment in closed position.

Figure 2 is a cross-section taken on the line 2—2 of Figure 1 looking toward the left.

Figure 3 is a cross-section taken on the line 3—3 of Figure 1, looking toward the left.

Figure 4 is a horizontal section taken on the line 4—4 of Figure 3, looking down.

My invention comprises a device manufactured of metal or other suitable material made up in units, each unit having one or more compartments, the units being adapted to be placed side by side and on top of each other if desired with practically no loss of space either between the units or between the individual compartments of each unit.

The units 1 are divided into compartments 2, arranged one on top of the other. Each compartment 2 is provided with a door 3 having a transparent glass window set therein so that the food in the compartments can be readily inspected from the outside when the doors are closed.

Each compartment is provided with a floor or bottom 5 on which the plates containing the articles of food are adapted to be placed. The sides of the unit, act as walls for the compartments 2. Door guides are secured to one of the walls of each compartment and to a partition 11 therein hereinafter described, each such guide having a sloping downwardly projecting front portion 6 and a horizontal rear portion 7. A sliding member 8 resting on the horizontal guide portion 7 is pivoted at its forward end to the top of the door 3 and is adapted to open and close the door 3 in the manner hereinafter described.

A coin-controlled door opening mechanism is provided at one side of each compartment. This mechanism is located in a narrow compartment 13 formed by an upright partition 11 in each food compartment 2 and a side wall 12 of the unit. This mechanism has a sliding coin-race 4, angularly disposed within the compartment 13, one end being normally in the rear lower corner thereof and the other end projecting through the front end 14 of the compartment 13 between lugs 45 and 46 near the

2
top thereof. A handle or knob 9 is formed on the upper projecting end of the coin-race 4, having a coin-receiving opening 10 therein. A plate 15 is welded or otherwise 5 secured to one side of the coin-race 4. This plate 15 is provided with a slot 16 having an arcuate portion or cam lift 17 at one end thereof. The slot 16 and cam lift 17 are located below the lower edge of the coin-race 4. A bolt or lug 43 secured to a plate 10 extends through the slot 16.

The plate 18 is secured to the partition 11 and extends substantially the entire length thereof. The plate 18 has threaded per- 15 forations 19 registering with similar perforations in the partition 11. A pin or bolt 20 is adapted to be placed in one or another of the perforations 19 and projects into the compartment 13. An upper coin guide or 20 stop 21 is secured to the plate 18 and ar- ranged immediately above and in substan- tially the same angular position as the coin-race 4. A lever 22 is pivotally secured to the bottom 5 by pivot pin 23. One end of 25 this lever 22 projects through slot 24 into the compartment 13 and the other end is pivotally secured to one end of a link 25 by pivot pin 26. The other end of the link 25 is pivotally secured to the forward part 30 of the sliding member 8 by pivot pin 27.

A locking lever 28 substantially triang- 35 ular in shape is pivotally secured at one corner to the plate 18 by pivot pin or bolt 29. The substantially horizontal side 30 of the locking lever 28 is provided near the end furthest from the pivot pin 29 with a notched portion 31 which is adapted to re- 40 ceive the end of the lever 22 projecting into the compartment 13. The side 30 beyond the notch 31 has a beveled end 32 so as to permit the lever 22 to slide into the notch 31 as will be hereinafter described.

The upper rear portion of the coin-race 4 is cut away and the downwardly project- 45 ing corner 33 of the locking lever 28 extends just slightly below the top of the coin-race 4. The rear portion 34 of the coin-race 4 is open at the top and has an open end 35. A pin 36 projects from the end 33 of the 50 locking lever 28 and has one end of a coiled spring 37 attached thereto. The other end of the spring 37 is attached to upwardly extending arm 39 of the plate 15 secured to the coin-race 4. The spring 37 tends to 55 bring the upper side 30 of the locking lever 28 into raised or locking position and acts as a return device for the coin-race 4. The plate 15 is provided at its rear end with an upwardly extending arm 40 which in turn 60 has a cross-piece 41 extending across the top of the coin-race 4 and arranged to come in contact with a downwardly projecting pin 42 on the lever 22.

The apparatus is operated in the follow- 65 ing way: The apparatus is first set to be

operated with a certain number of coins (according to the price of the food placed therein) by shifting the pin 20 to desired position. In the drawings it is shown in the third hole from the rear. This indicates 70 that the device should be operated with three coins. A sign giving the name of the food and the price thereof is usually placed on the front of the unit. Three coins are inserted in the coin slot 10 which roll down 75 the coin-race 4 until the first coin 47 strikes the side 44 of the locking lever 28. The distance between the open end 35 of the coin-race 4 and the side 44 is normally of less width than the diameter of a single coin 80 so that the coin cannot fall through. After the coins are in place, the knob 9 is grasped and pulled forward. In doing this, the coin-race 4 is first raised by movement of the cam lift 17 in the plate 15 upon the lug 43 85 and then pulled out, the direction of its movement being guided by the lug 43 in the slot 16 and lugs 45 and 46. As the coin-race 4 is raised it carries the three coins with it, the first coin 47 being in contact with the locking lever 28, until the last coin 48 strikes the projecting pin 20. Further upward movement of the coin-race causes the line of coins to bear against the locking lever 28 until it pivots about pivot pin 29, until 90 the notched portion 31 thereof is lowered sufficiently to disengage the lever 22. The upper coin guide 21 will prevent the coins from buckling or raising out of position. As the sliding coin-race 4 is pulled forward 100 the cross-piece 41 on the arm 40 of the plate 15 comes in contact with the downwardly projecting pin 42 on the lever 22 which is now out of engagement with the locking lever 28, and the lever 22 is caused to be pivoted about pivot pin 23. The lever 22 carries the link 25 and the sliding member 8 rearwardly thereby opening the door 2 which is first drawn back upon and up the inclined guides 6 and then upon the horizontal guides 7.

As the sliding coin-race 4 moves forward the coins drop therefrom into a coin chute 48 and from there go to a suitable coin box (not shown) located at the bottom of the unit. When the knob 9 is released the spring 37 brings the coin-race 4 back to its original position. The counter attendant or other person in charge of the apparatus upon seeing the sliding member 8 at the rear of the compartment projecting therefrom, immediately pushes it in and refills the compartment which may be open at the back. The forward movement of the sliding member 8 closes the door 2 and swings the lever 22 back into locked position in the notch 31 of the locking lever 28.

It will be readily seen that by changing the height of the line of perforations 19 in relation to the coin-race 4 and the distance 130

between these perforations the machine can be made to work with coins of any size or denomination.

Various modifications may be made in the embodiment of the apparatus herein described without departing from the spirit and scope of my invention.

I claim:

1. A coin-controlled apparatus comprising a compartment, a door therefor, a sliding member arranged to open and close the door, a toggle lever arrangement for operating the sliding member, means for operating the toggle lever arrangement consisting of a lock for the toggle lever member, a coin receiving member adapted to be partially withdrawn from the apparatus when coins are placed therein and release toggle lever member to open the door.

2. A coin-controlled apparatus comprising a compartment, a door therefor, a sliding member arranged to open and close the door, a toggle lever arrangement for operating the sliding member, means for operating the toggle lever arrangement consisting of locking means for the toggle lever member, a coin receiving member adapted to be partially withdrawn from the apparatus, said coin receiving member being adapted to receive a coin to positively actuate the locking means to release the toggle lever member to open the door when the coin receiving member is partially withdrawn from the apparatus.

3. A coin-controlled apparatus comprising a compartment, a door therefor, a sliding member arranged to open and close the door, a toggle lever arrangement for operating the sliding member, means for operating the toggle lever arrangement consisting of a locking member, a coin race adapted to be partially withdrawn from the apparatus when a coin is placed therein, means for moving the coin race to force the coin against the locking member to open same.

4. A coin-controlled apparatus comprising a compartment, a door therefor, a sliding member arranged to open and close the door, a toggle lever arrangement for operating the sliding member, means for operating the toggle lever arrangement consisting of a locking member, a coin race adapted to be withdrawn from the apparatus, said coin race being adapted to receive a coin, means for raising the coin race to bring the coin into forced contact with the locking member to open the same.

5. A coin-controlled apparatus comprising a compartment, a door therefor, a sliding member arranged to open and close the door, a toggle lever arrangement for operating the sliding member, means for operating the toggle lever arrangement consisting of a locking member, a coin race adapted to be partially withdrawn from the apparatus

when a coin is placed therein, means for moving the coin race to force the coin against the locking member to open same and means connected to the coin race adapted to engage the toggle lever member and 70 actuate same to open the door upon the forward movement of the coin race.

6. A coin-controlled apparatus comprising a compartment, a door therefor, a sliding member arranged to open and close the door, 75 a toggle lever arrangement for operating the sliding member, means for operating the toggle lever arrangement consisting of a locking member, a coin race adapted to receive a coin, a cam lift for raising the coin 80 race, and means for forcing the coin against the locking member to release the toggle lever member when the coin race is moved forward.

7. A coin-controlled apparatus comprising 85 a compartment, a door therefor, a sliding member arranged to open and close the door, a toggle lever arrangement for operating the sliding member, means for operating the toggle lever arrangement consisting of a locking member, a sliding coin race adapted 90 to receive a coin, a slotted member connected to the coin race arranged to raise the coin race when the coin race is moved and bring the coin into forced contact with 95 the locking member to release same.

8. A coin-controlled apparatus comprising a compartment, a door therefor, a sliding member arranged to open and close the door, a toggle lever arrangement for operating the 100 sliding member, means for operating the toggle lever arrangement consisting of a locking member, a sliding coin race adapted to receive a coin, a slotted member connected to the coin race arranged to raise 105 the coin race when the coin race is moved and bring the coin into forced contact with the locking member to release same, and means connected to the coin race adapted to engage the toggle lever member to actuate same to open the door.

9. A coin controlled apparatus comprising a food compartment, a partition in said compartment which together with the wall of the compartment furthest from the food 115 compartment forms mechanism containing compartment, perforations in the partition, a pin projecting through one of the perforations into the mechanism compartment, a door for the food compartment, door actuating means located at the top of the food compartment, a locking member for the door actuating means, a coin race adapted 120 to receive a coin, means for moving the coin race so that the coin will strike the projecting pin in the partition while in contact with the locking member and release the door actuating means.

10. A coin-controlled apparatus comprising 125 a food compartment, a partition in said

compartment which together with the wall of the compartment furthest from the food compartment forms mechanism containing compartment, perforations in the partition, 5 a pin projecting through one of the perforations into the mechanism compartment, a door for the food compartment, door actuating means located at the top of the food compartment, a locking member for the 10 door actuating means, a coin race adapted to receive a coin, means for moving the

coin race so that the coin will strike the projecting pin in the partition while in contact with the locking member and release the door actuating means, and means connected 15 to the coin race for positively actuating the door actuating means to open the door.

In testimony whereof, I have signed my name to this specification this 16th day of September, 1921.

JOSEPH N. BURNO.
